WINDOW CLEARANCE SLOT COVER

Carl E. Hedeen, Grosse Pointe Woods, James C. Lou-ton, Jr., Utica, and Henry J. Wubbe, Royal Oak, Mich., assignors to General Motors Corporation, Detroit, Mich., a corporation of Delaware

Application July 31, 1958, Serial No. 752,231

10 Claims. (Cl. 296—44)

This invention relates to a window clearance slot cover, and more particularly to a window clearance slot cover which is arranged to close a window clearance slot when the window is closed and to swing out of the way to permit rearward and downward movement of a window in an automobile door.

Automobile door windows conventionally are arranged to drop down within the door to an open position. In many body constructions a straight downward movement of the window is all that is required; however, in certain body constructions it is necessary to move the window in an endwise direction relative to the door as well as downwardly. Under these conditions it is necessary to provide a clearance slot in the door adjacent an edge of the window to permit endwise movement of the window. This invention provides a pivotally mounted cover member for closing the clearance slot when the window is up, and means are provided for automatically locking the cover member in slot-closing position when the window is closed to prevent access to the interior of the door from outside the automobile through the clearance slot. The cover member may be pivotally mounted either on the window or on the door, and the cover member carries a follower which is adapted to engage a guide member for swinging the cover toward a slot-closing position as the window moves toward closed position and for locking the cover in slot-closing position when the window is closed.

Other features and advantages of the invention will be apparent from the following description and from the drawings, in which:

Fig. 1 is a fragmentary side elevational view of an automobile having a preferred form of the invention therein, a portion of the automobile door outer panel being broken away to show underlying parts, and the window and associated structure being shown fragmentarily in open position in broken lines;

Fig. 2 is an enlarged fragmentary view of a portion of the structure of Fig. 1;

Fig. 3 is a horizontal section taken along the line 3—3 of Fig. 2;

Fig. 4 is a detail section taken along the line 4—4 of Fig. 2;

Fig. 5 is a view similar to Fig. 2 but showing a modified form of the invention, the parts being shown in solid lines with the window closed and in broken lines with the window partially open;

Fig. 6 is a horizontal section taken along the line 6—6 of Fig. 5;

Fig. 7 is a vertical section taken along the line 7—7 of Fig. 5; and

Fig. 8 is a detail section taken along the line 8—8 of Fig. 5.

Referring now more particularly to the drawings, an automobile designated in Fig. 1 generally as 10 has a body including a rear quarter 12, a center pillar 14, a rocker panel 16, and a roof 18 which carries a back

2

window 20. A fixed rear quarter window 22 is mounted between the rear quarter 12 and the roof 18. As part of the body, a front door is shown fragmentarily at 24 and a rear door is designated generally as 26 and includes 5 an outer panel 28 and an inner panel 30. The rear door 26 is hingedly mounted in conventional manner (not shown) on the center pillar 14. Conventional door latches (not shown) may be used to latch each door. The rear door 26 mounts a window 32 and carries a peripheral 10 frame 34 including a top member 34a, a rear side member 34b, a front side member 34c, and a bottom member 34d. The window is adapted to be moved between a closed position shown in solid lines in Fig. 1 and shown fragmentarily in broken lines in Fig. 2 and an open position shown fragmentarily in broken lines in Fig. 1, wherein the window has moved downwardly and rearwardly and is housed in the door between the outer and inner panels 28, 30 thereof. Any suitable type of regulator mechanism may be utilized to move the window between its closed and 20 open positions, as for example, a regulator of the type shown in Patent No. 2,775,479 which issued on December 25, 1956, to J. J. Balint et al.

As may be seen in Fig. 1, center pillar 14 is offset rearwardly relative to the front member 34c of the 25 window frame and the rear portion of the door 26 extends back into the rear quarter 12 past the rear edge of the window 32. Because of the rearwardly offset center pillar, it is not possible to drop the window 32 straight down from closed to open position, but the window must 30 move rearwardly as it moves downwardly in order to clear the center pillar. The rear portion of the door which extends into the rear quarter 12 provides space for this movement. Mounted in the door are window guides 36 and 38 which are connected to the window through 35 rollers 36a and 38a carried on a horn 34f projecting downwardly from the bottom member 34d of the window frame and which guide the window in a downwardly and rearwardly extending path during the first part of window movement from closed toward open position.

40 A window clearance slot 40 is formed in a horizontally bent upper portion of the outer door panel 28 at the belt line of the automobile to receive the rear edge of the window 32 as the window moves downwardly and rearwardly. The window 32 and the slot 40 are both located 45 in a vertical plane outwardly of the plane of the fixed rear quarter window 22 to permit the necessary rearward movement of the door window 32.

This invention provides a novel cover member for 50 closing the slot 40 when the window is closed, and means are provided for automatically locking the cover in slot-closing position when the window is moved to closed position to prevent access into the inside of the door from outside the automobile through the clearance slot 40. 55 In the preferred form of the invention shown in Figs. 1 through 4, the cover member is pivotally mounted on the window frame and engages a guide channel on the door for holding the cover in slot-closing position. Figs. 5 through 8 show a modified form of the invention which is generally similar except that the cover member 60 is pivotally mounted on the door and engages guide or holding means on the window.

In Figs. 1 through 4 a cover member, which is formed as an inverted channel, is designated generally as 42 and includes an outer wall 42a, an inner generally parallel wall 42b, and a top generally horizontal web portion 42c. At one end of the cover member each of the opposite walls is extended forwardly past the forward end of the web portion 42c to provide yoke arms which straddle the bottom window frame member 34d, and a pin 44 extends through the yoke arms and the frame member 34d to pivotally mount the cover member 42 on the window. A bracket 42d is welded to the inner wall 42b

of the cover member and projects downwardly therefrom, terminating in an inwardly bent end 42e having rolled front and rear edges as shown best in Fig. 2 and forming a follower. A tension spring 46 is connected at its forward end to a horn 34e projecting downwardly and forwardly from the bottom member 34d of the window frame and the spring is connected at its rear end to the outer wall 42a of the cover member so that the spring resiliently urges the cover member in a counterclockwise direction as the parts appear in Fig. 1 from the operative or slot-closing position shown in full lines toward an inoperative position shown in broken lines. Mounted on the inner door panel 30 is a bracket 48 carrying guide means comprising a wall flange 52 extending obliquely downwardly in a direction forwardly of the door 26. When the window 32 is closed as illustrated in full lines in Fig. 1, the cover member 42 is in its horizontal slot-closing position, the follower 42e seating adjacent the wall flange 52 so that the cover is locked in its slot-closing position and access to the interior of the door through the slot 40 is prevented. Downward pressure on the web portion 42c of the cover will not swing the cover down because of the engagement of the follower 42e with the wall flange 52. When the window is moved toward open position, it moves downwardly and rearwardly in a path defined by the window guides 36, 38, and the window carries the cover member 42 bodily rearwardly and downwardly so that the follower 42e moves away from and down past the wall flange 52, permitting the spring 46 to swing the cover member in a counterclockwise direction to the inoperative position illustrated in broken lines in Fig. 1. As the window moves from open position toward closed position, the follower 42e engages the wall flange 52 so that the cover member is cammed up to a horizontal position during the final closing movement of the window, whereby the cover swings into its slot-closing position and is locked therein by interengagement of the follower 42e on the cover with the wall flange 52 on the door.

In the modification of the invention illustrated in Figs. 5 through 8, the general body construction of the automobile is the same and the same reference characters are used. The cover is pivoted on the door and the guide channel which swings the cover toward slot-closing position as the window moves toward closed position and locks the cover in slot-closing position when the window is closed is located on the window frame.

Referring to Figs. 5 through 8, a cover member designated generally as 142 has an outer wall 142a and an inner wall 142b connected by a web 142c. Each of the outer walls has yoke extensions whereby the cover member is pivotally mounted on a bracket 143 bolted in the door by means of a pin 144. A torsion spring 146 mounted on the pin 144 yieldably urges the cover member in a counterclockwise direction toward slot-closing position. At its forward end the cover member has an extension 142d terminating at its forward end in a follower 142e adapted to cooperate with a guide channel 150 formed in the bottom window frame member 34d.

The operation of the modified species shown in Figs. 5 through 8 is generally similar to the operation of the preferred species shown in Figs. 1 through 4. When the window 32 is closed, the follower 142e seats in the guide channel 150 to lock the cover member in its slot-closing position. When the window moves downwardly and rearwardly, it cams the cover member 142 in a clockwise direction as shown in broken lines in Fig. 5 until the follower 142e clears the open end of the guide channel 150. As the window moves toward fully open position the spring 146 holds the cover against the rear edge of the rear window frame member 34b.

When the window is moved toward closed position, the cover rides along the rear edge of the rear window frame member 34b until the window reaches the position shown in broken lines in Fig. 5, whereupon the cover

swings in a counterclockwise direction under force exerted by the spring 146 so that the follower 142e enters the guide channel 150 on the window frame 34d and the cover is swung up to slot-closing position by the guide channel 150 as the window closes. With the window closed, downward pressure on the cover will not swing the cover away from the mouth of the window clearance slot because of the engagement of the follower 142e in the guide channel 150.

While we have shown and described two embodiments of our invention, it is capable of many modifications. Changes, therefore, in the construction and arrangement may be made without departing from the spirit and scope of the invention as set forth in the appended claims.

We claim:

1. In combination, an automobile body member, a window member mounted on the body member for movement downwardly and in an endwise direction relative to the body member between closed and open positions, said body member having a slot therein for receiving an edge of the window member during such endwise movement, a cover for closing said slot when the window member is in closed position, said cover having a follower thereon, means pivotally mounting said cover on one of said members for movement between slot-closing position and inoperative position, and guide means on the other of said members adapted to engage said follower to swing said cover toward slot-closing position as the window member moves toward closed position and for locking said cover in slot-closing position when the window member is closed.

2. In combination, an automobile body member, a window member mounted on the body member for movement downwardly and in an endwise direction relative to the body member between closed and open positions, said body member having a slot therein for receiving an edge of the window member during such endwise movement, a cover for closing said slot when the window member is in closed position, said cover having a follower thereon, means pivotally mounting said cover on one of said members for movement between slot-closing position and inoperative position, and guide means on the other of said members adapted to engage said follower to swing said cover toward slot-closing position as the window member moves toward closed position and for locking said cover in slot-closing position when the window member is closed, and spring means resiliently urging said cover toward its inoperative position.

3. In combination, an automobile body member, a window member mounted on the body member for movement downwardly and in an endwise direction relative to the body member between closed and open positions, said body member having a slot therein for receiving an edge of the window member during such endwise movement, window guide means on the body member connected to the window member for guiding movement thereof between closed and open positions, a cover for closing said slot when the window member is in closed position, said cover having a follower thereon, means pivotally mounting said cover on one of said members for movement between slot-closing position and inoperative position, guide means on the other of said members adapted to engage said follower to swing said cover toward slot-closing position as the window member moves toward closed position and for locking said cover in slot-closing position when the window member is closed, and spring means resiliently urging said cover toward its inoperative position.

4. In combination, an automobile door member, a window member mounted on the door member for movement downwardly and rearwardly relative to the door member between open and closed positions, said door member having a slot therein for receiving an edge of the window member during such rearward movement, a cover for closing said slot when the window member is

in closed position, said cover having a downwardly projection extension providing a follower, means pivotally mounting said cover on one of said members for movement between slot-closing position and inoperative position, and guide means on the other of said members adapted to engage said follower to swing said cover toward slot-closing position as the window member moves toward closed position and for locking said cover in slot-closing position when the window member is closed.

5. In combination, an automobile body member, a window mounted on the body member for movement downwardly and in an endwise direction relative to the body member between closed and open positions, said body member having a slot therein for receiving an edge of the window during such endwise movement, a cover for closing said slot when the window is in closed position, said cover having a follower thereon, means pivotally mounting said cover on said window for movement between slot-closing position and inoperative position, and guide means on said body member adapted to engage said follower to swing said cover toward slot-closing position as the window moves toward closed position and for locking said cover in slot-closing position when the window is closed.

6. In combination, an automobile door, a window mounted on the door for movement downwardly and in an endwise direction relative to the door between closed and open positions, said door having a slot therein for receiving an edge of the window during such endwise movement, a cover for closing said slot when the window is in closed position, said cover having a follower thereon, means pivotally mounting said cover on said window for movement between slot-closing position and inoperative position, guide means on said door adapted to engage said follower to swing said cover toward slot-closing position as the window moves toward closed position and for locking said cover in slot-closing position when the window is closed, and spring means resiliently urging said cover toward its inoperative position.

7. Apparatus of the character claimed in claim 6, wherein said guide means comprises a member on the door having a guide flange which extends downwardly and obliquely in an endwise direction opposite to the endwise direction in which said window moves from closed to open position.

8. In combination, an automobile door, a window mounted in the door for movement downwardly and rearwardly relative to the door between closed and open positions, said door having a slot therein for receiving an edge of the window during such rearward movement,

guide means on the door connected to the window for guiding movement of the window, a cover for closing said slot when the window is in closed position, said cover having a follower thereon, means pivotally mounting said cover on said window for movement between slot-closing position and inoperative position, guide means on the door adapted to engage said follower to swing said cover toward slot-closing position as the window moves toward closed position and for locking said cover in slot-closing position when the window is closed, and spring means resiliently urging said cover toward its inoperative position.

9. In combination, an automobile body member, a window mounted on the body member for movement downwardly and in an endwise direction relative to the body member between closed and open positions, said body member having a slot therein for receiving an edge of the window during such endwise movement, a cover for closing said slot when the window is in closed position, said cover having a follower thereon, means pivotally mounting said cover on said body member for movement between slot-closing position and inoperative position, and guide means on said window adapted to engage said follower to swing said cover toward slot-closing position as the window moves toward closed position and for locking said cover in slot-closing position when the window is closed.

10. In combination, an automobile door, a window mounted on the door for movement downwardly and rearwardly relative to the door between closed and open positions, said door having a slot therein for receiving an edge of the window during such rearward movement, a cover for closing said slot when the window is in closed position, said cover having a follower thereon, means pivotally mounting said cover on said door for movement between slot-closing position and inoperative position, guide means on said window adapted to engage said follower to swing said cover toward slot-closing position as the window moves toward closed position and for locking said cover in slot-closing position when the window is closed, and spring means resiliently urging said cover toward its inoperative position.
